UNITED STATES PATENT OFFICE.

JAMES T. COWLEY, OF SYRACUSE, NEW YORK, ASSIGNOR TO THE LAMSON COMPANY, OF SYRACUSE, NEW YORK, A CORPORATION OF MASSACHUSETTS.

PNEUMATIC-DISPATCH POWER-CONTROL APPARATUS.

Application filed April 25, 1925. Serial No. 25,766.

This invention pertains to power controllers for pneumatic dispatch systems and relates more particularly to automatically actuated controllers of the so-called "minimum flow" type of which the patent to Libby No. 968,578, August 30, 1910, furnishes a familiar example.

Controllers of this type comprise essential-
ly a valve located between the transmission
tube and an air exhauster or vacuum drum,
such valve normally cutting off carrier pro-
pelling air flow through the tube when the
tube is idle, although at all times permitting
a continuous flow of relatively small volume
insufficient to propel a carrier and known
as the "minimum flow," and a pneumatic, for
example a piston or diaphragm, which re-
sponds, either directly or indirectly, to
change in pressure in the tube, due to the
momentary cutting off or checking of the
minimum flow of air incident to the inser-
tion of a carrier in the tube, and which, by
such response, opens wide the valve to per-
mit a full carrier propelling air flow through
the transmission tube.

In the form of apparatus described in the Libby patent the period during which the valve remains open is determined solely by the operation of a timing device. The present invention is intended to improve the operation of devices of this general type by eliminating the timing device and in place thereof providing means which is responsive directly to the change in pressure in the transmission tube, incident to discharge of the last carrier therefrom, for initiating closure of the controlling valve.

In the accompanying drawings a preferred embodiment of the invention is illustrated by way of example,—

Fig. 1 being a diagrammatic elevation, partly in section, showing the improved controller installed between one transmission tube of a pneumatic system and the exhaust header thereof;

Fig. 2 is a vertical section to large scale showing the parts in normal position, the main valve being closed; and

Fig. 3 is a view similar to Fig. 1 but showing the parts as positioned at the instant

after discharge of the last carrier from the tube but before the main valve has closed.

Referring to Fig. 1 of the drawings, the numeral 1 indicates a portion of a central station desk provided with the dispatch terminal 2 forming a part of the sending transmission tube 3 leading to an outlying station. The corresponding return transmission tube 4 is provided with the usual delivery terminal 5 and with an extension 6 which passes down through the top of the desk 1 and is connected with the power control apparatus indicated generally at 7. A suction tube 8 leads from the power control apparatus to the usual section drum or header 9 in which a vacuum is constantly maintained by means of a suitable exhauster, not shown. A continuous air passage or conduit is thus provided extending from the terminal 2 to the exhauster, that portion of the conduit 70 provided by the tubes 3 and 4 constituting the carrier transmission line.

Referring to Figs. 2 and 3, the numeral 7 as above explained indicates the improved power controller as a whole. This controller in the embodiment illustrated comprises a hollow casing 10 having therein a chamber 10^a which communicates freely at all times with the pipe 8 leading to suction header 9. A substantially U-shaped partition or septum 11, comprising substantially parallel upper and lower walls 12 and 13 respectively, separates the main body of the chamber 10^a from an inlet chamber 14 which communicates directly with the tube 6.

The upper and lower walls 12 and 13 of the septum 11 are furnished with aligned valve orifices 15 and 16 respectively (Fig. 3). A valve 17 of balanced type, herein-after referred to as the "main valve" and comprising spaced heads 18 and 19, cooperates with the orifices 15 and 16, and controls the inward flow of air through the transmission tubes 3 and 4 toward the exhaust header 9. Normally the valve 17 is closed so as to cut off carrier propelling air flow through the transmission tubes, but at all times a small continuous flow of air through the transmission tube is permitted by the provision of a conduit 20 leading directly from the

pipe 6 to the pipe 8 outside of the controller casing 10. While such an outside pipe is preferred, similar results may be obtained if desired by providing a small orifice through one of the walls of the septum 11 or alternatively by making the valve heads 18 and 19 somewhat smaller than the valve orifices so as to allow leakage of air past the valve heads.

10 The upper wall 21 of the controller casing 10 is flared outwardly and upwardly to provide a shallow receptacle 22 of generally circular contour which has a radial flange 23 at its edges. This flange forms a seat for 15 the outer edge of a flexible diaphragm 24 which is clamped between the flange 23 and the marginal flange 25 of a downwardly concave cover member 26, secured to the flange 23 in any desired manner, for example by 20 means of bolts, not shown. The members 22 and 26 thus constitute a pneumatic motor casing which is divided by the diaphragm 24 into upper and lower chambers 27 and 28 respectively. The lower chamber 28 communicates freely at all times with the outer chamber by means of one or more large orifices 29 in the member 22, while the chamber 27 communicates with the atmosphere by means of a single small orifice 29^a preferably controlled by an adjustable needle valve.

25 The central part of the diaphragm is preferably clamped between plates 30 and 31 disposed upon its opposite sides and is secured to the upper end of the stem 32 of the valve 17 by means of a bolt 33 which passes through the plates 30 and 31 and the central part of the diaphragm and has threaded engagement with an axial opening in the stem 32. For convenience in assemblage of the parts it is preferred to provide the upper wall 21 of the casing 10 with a central aperture which is normally covered by a removable plate 34 having a boss 35 provided with a guideway for the stem 32 of the valve.

30 A rod 36 forming an extension of the stem 32 has screw-threaded engagement at its lower end with a threaded opening in the head of the bolt 33. This rod 36 passes through a guide opening in the upper end of a gland 37 having threaded engagement with an opening in a boss 38 projecting from the cover 26. One end of a compression spring 39 bears against the inner surface of the gland 37. This spring encircles the rod 36 and bears at its lower end against a collar 40 secured to the rod 36. By screwing the gland 37 in or out the tension of the spring 39 may be varied, the tendency of the spring being to depress the diaphragm 34 and to retain it in the normal position indicated in full lines in Fig. 2. The upper end of the rod 36 is screw-threaded for the reception of an adjustable contact thimble 42.

35 The cover 26 is provided at one side with

an upstanding boss 43 which forms a support for the base member of the casing of an auxiliary motor pneumatic, such casing comprising the lower saucer-like receptacle 44 having a radial flange 45 at its edge which forms a seat for the edge of a flexible diaphragm 46. The edge of the diaphragm is clamped between the flange 45 and the flange 47 of the downwardly concave cover member 48 of the auxiliary motor casing.

40 The central part of the diaphragm 46 is preferably clamped between stiffening plates 49. This diaphragm is provided with a stem member 50 sliding in a suitable guide opening in a boss 50^a at the center of the base member 44 of the auxiliary motor casing. The upper end of the stem 50 passes through the diaphragm and the plates 46 and is screw threaded for engagement by a clamping nut 51. The stem 50 is furnished with a restricted axial passage 53 of small cross section which opens laterally through the side of the stem at the point 54 outside of the auxiliary motor casing and which opens at its upper end at the point 55 into the upper chamber of the auxiliary motor.

45 A valve disk 56 is secured to the lower end of the stem 50 and cooperates with an annular valve seat 57 defining a valve orifice 58 which connects the chamber 27 of the main motor with a passage 59 which leads to the chamber 14 of the controller casing.

50 A gland 61 has threaded engagement with an opening in a boss 62 projecting from the top of the cover member 48 of the auxiliary motor casing. This gland is hollow and provides a seat for the upper end of a coiled compression spring 63 whose lower end bears against the clamping nut 51 of the stem 50. The spring thus tends to depress the diaphragm 46 to restore it to the normal position indicated in Fig. 2. By turning the gland 61 the tension of the spring may be varied.

55 A bracket 66 is secured to the cover member 48 of the auxiliary motor casing and forms a support for a pivot pin 67 constituting the fulcrum of a lever 68 which is arranged to swing in the vertical plane defined by the stems 36 and 50. One end of a spring 78 is secured to the lever 68 at the point 73. The other end of the spring is secured to an eye bolt 74 passing freely through suitable openings in the flanges of the main motor casing and which is provided with an adjusting nut 75 at its lower end.

60 The opposite end of the lever 68 is guided in its vertical swinging movement by a slot 70 in a bracket 71 secured to the top of a boss 80 projecting from the cover 48 of the auxiliary motor casing.

65 The boss 80 is furnished with a chamber 81 opening into the upper chamber 48^a of the auxiliary motor. A vent passage 82 leads upwardly from the chamber 81 to the

outer air and at the junction of this passage with the chamber 81 a valve seat surface 83 is provided.

A suitable vent valve, preferably a ball valve 84, is arranged within the chamber 81 and adapted to seat against the surface 83 to close the passage 82. This valve is secured to the lower end of the stem 85 extending loosely through the passage 82 and pivotally connected at the point 86 to the end 87 of the lever 68. The spring 78 is so tensioned as normally to retain the ball valve 84 against its seat so as to close the passage 82 and thereby to prevent entrance of air at atmospheric pressure into the upper chamber of the motor casing.

The operation of the device is substantially as follows, it being assumed that when the transmission tube is idle the parts occupy the position indicated in full lines in Fig. 2. When in this position the member 42 is spaced from the lower edge of the lever 68, the latter being substantially horizontal, and the valve 84 rests against its seat. At this time a minimum flow of air is entering the open transmission terminal 2 of the tube 3 and circulating through the outlying station, the tube 4, pipe 6, and tube 20, is passing to the exhauster.

When a carrier is inserted in the transmission tube, either at the point 2 or at the outlying station, the minimum flow of air is cut off or at least substantially diminished with resultant increase in the vacuum in the transmission line. This decrease in pressure is immediately transmitted through the passage 59 and the open valve orifice 58 to the chamber 27 of the main motor where it becomes effective to raise the diaphragm 24 against the resistance of the spring 39 and thus to open the main valve 17. As soon as the main valve opens to the slightest degree the vacuum in the transmission tube is further increased so that the diaphragm 24 rises with increasing force until the main valve is fully open. As the main valve approaches its fully open position the contact member 42 engages the lower edge of the lever 68 and tilts the latter to the dotted line position indicated at 76 in Fig. 2, the resistance of spring 68 being added to that of spring 39 in opposing this final movement of diaphragm 24. This moves the end 87 of the lever downwardly and thus unseats the valve 84 permitting atmospheric pressure to enter freely into the upper chamber of the auxiliary motor casing.

While the above operations were taking place and prior to the opening of the valve 84, the decreased pressure in the passage 59 resulting first from insertion of the carrier into the transmission tube, and second from opening the main valve is slowly transmitted through the passage 53 to the upper cham-

ber 48^a of the auxiliary motor. As the lower chamber 48^b of this motor is always freely open to the atmosphere through a vent 44^a, the diaphragm 46 tends to rise and thus to close the valve 56, but as the passage 53 is so restricted the differential pressures acting upon the opposite sides of the diaphragm 46 fail to lift the diaphragm in opposition to the spring 63 until the main valve has had time fully to open and thus to unseat the valve 84.

So long as the valve 84 remains unseated the slow withdrawal of air from the chamber 48^a is unavailing to raise the diaphragm 46 so that the valve 56 remains open.

When the last carrier emerges from the transmission tube, the vacuum in the transmission tube decreases slightly by reason of the removal of the frictional drag of the carrier passing along the tube. This slight increase in pressure in the transmission tube permits the diaphragm 24 to move down to a slight extent responsive to its spring 39, assisted by the spring 73, until the lever 68 is restored to its normal position as indicated in Fig. 3. This movement of the lever 68 closes the valve 84 whereupon the pressure in the upper chamber 48^a of the auxiliary motor gradually decreases until the diaphragm 46 rises to close the valve 56.

As the valve chamber 27 is now no longer connected to the transmission tube, atmospheric air leaks in through the valve aperture 29^a until the pressure upon opposite sides of the diaphragm 29 has been nearly equalized, whereupon the spring 39 depresses the diaphragm 24 and closes the main valve 17, thus cutting off the carrier propelling air flow through the transmission tube.

As soon as such flow is cut off the pressure in the chamber 48^a begins slowly to rise as the air leaks in through the passage 56 and after a short interval the spring 63 restores the valve 56 to its normal open position.

By the arrangement described the opening of the main valve is accomplished automatically by the slight drop in pressure in the transmission tube incident to introduction of a carrier, and this valve is positively held open until the last carrier emerges from the line. The slight increase in pressure incident to the delivery of the last carrier then initiates closure of the main valve. The device thus operates independently of any timing arrangement and solely in accordance with the presence or absence of a carrier or carriers in the transmission tube.

In my copending application, Serial No. 25,765, filed April 25, 1925, I have disclosed a modified arrangement for determining the time of closure of the auxiliary valve and have therein claimed my invention broadly.

While I have herein illustrated a preferred

embodiment of the invention, I wish it to be understood that various changes in relative position and proportion of parts, as well as the substitution of equivalents for the elements herein specifically described may be made without departing from the spirit of the invention.

I claim:

1. Power control apparatus for a pneumatic dispatch system of the vacuum minimum flow type having a transmission tube communicating with an exhauster, said apparatus comprising a main valve for controlling carrier propelling air flow through the tube, a minimum flow of air through the tube being permitted when the valve is closed, a main pneumatic for operating the controlling valve, an auxiliary pneumatic, an auxiliary valve actuatable by the auxiliary pneumatic to vary the pressure acting upon the main pneumatic, means tending to establish unbalanced pressure upon opposite sides of the auxiliary pneumatic when a carrier is inserted in the transmission tube and means actuatable by the main pneumatic to maintain a balanced pressure upon opposite sides of the auxiliary pneumatic so long as a carrier remains in the transmission tube.

2. Power control apparatus for a pneumatic dispatch system having a transmission tube, means for creating carrier propelling air flow therein, said apparatus comprising a main valve for controlling carrier propelling air flow through the tube, a main motor for operating the controlling valve, control means for the main motor, a pneumatic constantly exposed upon one side to atmospheric pressure, a normally closed pressure control valve for determining admission of atmospheric pressure to the opposite side of the pneumatic, means for transmitting movement from the main motor to said pressure control valve to open the latter and to hold it open so long as a carrier remains in the transmission tube, and means for transmitting movement from the pneumatic to the control means of the main motor.

3. Power control apparatus for a pneumatic dispatch system of the vacuum minimum flow type having a transmission tube communicating with an exhauster, said apparatus comprising a main valve for controlling carrier propelling air flow through the tube, a minimum flow of air through the tube being permitted when the valve is closed, a main pneumatic for operating the controlling valve, an auxiliary pneumatic, a normally closed vent valve for admitting atmospheric pressure to act upon one side of said auxiliary pneumatic, a constantly open restricted passage leading from the transmission tube to the space at said side of the auxiliary pneumatic pressure control means for the main pneumatic actuatable by the auxiliary pneumatic, and connections between

the main pneumatic and the vent valve for opening the latter.

4. Power control apparatus for a pneumatic dispatch system having a transmission tube, and means for creating carrier propelling air flow therein, said apparatus comprising a main valve for controlling carrier propelling air flow through the tube, a main motor for operating the valve, control means for the main motor, a pneumatic for actuating said control means, a passageway constantly open being provided through which transmission tube pressure may be transmitted at all times to the space at one side of the auxiliary pneumatic thereby tending to actuate the latter and thereby operate the control means for the main motor, and means actuatable by the main motor to prevent the establishment of transmission line pressure in said space so long as a carrier remains in the transmission tube.

5. Power control apparatus for a pneumatic dispatch system of the vacuum minimum flow type having a transmission tube communicating with an exhauster, said apparatus comprising a main valve for controlling carrier propelling air flow through the tube, a minimum flow of air through the tube being permitted when the valve is closed, a main pneumatic for moving the controlling valve, said pneumatic having a chamber communicating by means of a normally open passage with the transmission tube, an auxiliary valve for closing said passage, an auxiliary pneumatic for moving the auxiliary valve, said auxiliary pneumatic having a chamber normally closed to atmospheric pressure, a normally closed vent valve for admitting atmospheric air to said latter chamber, and means actuatable by the first named pneumatic for opening said vent valve.

6. Pneumatic dispatch apparatus having a transmission tube, and means for creating carrier propelling air flow therein, and a valve for controlling the flow of air through the transmission tube, a fluid motor for operating the air controlling valve, an auxiliary valve for controlling pressure conditions in said fluid motor, a pneumatic for closing the auxiliary valve, the pressure upon opposite sides of said pneumatic tending to become unbalanced when a carrier is inserted in the tube, a vent valve for the pneumatic and means for transmitting movement from said fluid motor to the vent valve to open the latter and thereby to maintain a substantially equal pressure upon opposite sides of the pneumatic as long as a carrier remains in the tube.

7. Pneumatic dispatch apparatus having a transmission tube, an exhauster connected therewith, and a valve for controlling the flow of air through the transmission tube, a minimum flow of air through the tube being

permitted when the valve is in closed position, a pneumatic main motor comprising a flexible diaphragm for operating the air controlling valve, said diaphragm being connected to said valve, an auxiliary valve for controlling pressure conditions in the main motor, an auxiliary pneumatic motor comprising a flexible diaphragm connected to the auxiliary valve, the pressure upon opposite sides of said auxiliary diaphragm tending to become unbalanced and thereby to close the auxiliary valve when a carrier is inserted in the transmission tube, and means actuatable by the main motor to preserve substantial equality of pressure upon opposite sides of said diaphragm so long as a carrier remains in the tube.

8. Pneumatic dispatch apparatus having a transmission tube, and means for creating carrier propelling air flow therein, and a main valve for controlling the flow of air through the transmission tube, a pneumatic main motor comprising a flexible diaphragm for operating the main valve, means connecting said diaphragm to said main valve, an auxiliary valve for controlling pressure conditions in the main motor, an auxiliary pneumatic motor comprising a flexible diaphragm connected to the auxiliary valve, one side of the auxiliary diaphragm being exposed to atmospheric pressure, the pressure upon the other side of said diaphragm tending to drop below atmospheric pressure when a carrier is placed in the transmission tube and thereby to close said auxiliary valve, a normally closed vent valve to admit atmospheric air to act upon said last named side of the pneumatic, means actuatable by the main motor for opening said vent valve when a carrier is placed in the tube and for holding said vent valve open so long as a carrier remains in the tube, and means tending to close the vent valve.

9. Power control apparatus for a pneumatic dispatch system of the vacuum minimum flow type having a transmission tube communicating with an exhauster, said apparatus comprising a main valve for controlling carrier propelling air flow through the tube, a minimum flow of air through the tube being permitted when the valve is closed, a main pneumatic for operating the valve, a pressure control valve for the main pneumatic, a motor for actuating said control valve, said motor having a chamber, a flexible diaphragm forming one wall of the chamber, means connecting the diaphragm to the pressure control valve, there being a restricted passage for transmitting transmission tube pressure to said chamber, a vent valve for admitting atmospheric air to said chamber, the main pneumatic responding to drop in transmission tube pressure due to insertion of a carrier and thereby opening the main valve, and connections between the

main pneumatic and the vent valve constructed and arranged to open the latter as the main valve reaches its fully open position, said vent valve remaining open so long as a carrier remains in the transmission tube. 70

10. Power control apparatus for pneumatic dispatch system having a transmission tube and means for creating a carrier propelling air flow therein, said apparatus comprising a main valve for controlling carrier propelling air flow through the tube, a main pneumatic for operating the main valve, a pressure control valve for the main pneumatic, a motor for actuating said control valve having a chamber, a flexible diaphragm 75 forming one wall of the chamber, means connecting the diaphragm to the pressure control valve, there being a restricted passage for transmitting transmission tube pressure to said chamber, a vent valve for 80 controlling admission of atmospheric air to said chamber, the main pneumatic responding to change in pressure in the transmission tube due to insertion of a carrier therein, thereby to open the main valve, a lever 85 connected to the vent valve, and means actuatable by the main pneumatic as the main valve approaches fully open position for rocking the lever and thereby moving the vent valve. 90

11. Power control apparatus for a pneumatic dispatch system having a transmission tube and means for creating carrier propelling air flow therein, said apparatus comprising a main valve for controlling carrier propelling air flow through the tube, a main motor for operating the valve, control means for the main motor, a pneumatic motor for actuating said control means, said pneumatic motor having a chamber, a flexible diaphragm forming one wall of the chamber, means connecting the diaphragm to the control means for the main motor, there being a restricted passage for transmitting transmission tube pressure to said 100 chamber, a vent valve for controlling admission of atmospheric air to said chamber, the main motor having a reciprocating member, a lever having an element disposed in the path of movement of said reciprocating member but normally spaced therefrom, means connecting said lever to the vent valve, and means acting upon the lever tending to close the vent valve, the main motor responding to insertion of a carrier 110 in the transmission tube to open the main valve and to rock said lever whereby fully to open the vent valve, said main motor also responding to discharge of the last carrier from the transmission tube to permit the 120 vent valve completely to close. 115

12. Power control apparatus for a pneumatic dispatch system of the vacuum minimum flow type having a transmission tube communicating with an exhauster, said ap- 130

paratus comprising a main valve for controlling carrier propelling air flow through the tube, a minimum flow of air through the tube being permitted when the valve is closed, a main pneumatic motor for moving the controlling valve, said motor having a casing divided into chambers by a movable septum, one of said chambers being freely open to the atmosphere and the other chamber communicating by means of a passage with the transmission tube, a normally open auxiliary valve for closing said passage, said auxiliary valve having a stem, an auxiliary pneumatic motor comprising a casing divided into chambers by a movable septum, means connecting the movable septum to the stem of the auxiliary valve, one of the chambers of the auxiliary motor being freely open to the atmosphere and the other normally closed to the atmosphere but communicating by means of a restricted passage through the valve stem with the transmission tube, a normally closed vent valve for admitting atmospheric air to the latter chamber of the auxiliary motor, means tending to close said vent valve, and means actuatable by the main motor for opening said vent valve and holding it open during flight of a carrier through the tube.

13. Power control apparatus for a pneumatic dispatch system of the vacuum minimum flow type having a transmission tube

communicating with an exhauster, said apparatus comprising a main valve for controlling carrier propelling air flow through the tube, a minimum flow of air through the tube being permitted when the valve is closed, a main pneumatic motor comprising a casing having a chamber therein, a diaphragm forming one wall of said chamber, said chamber normally communicating by means of a passage with the transmission tube, the diaphragm having a stem connecting it with the main valve, an auxiliary valve controlling said passage, an auxiliary pneumatic motor comprising a casing having a chamber, a flexible diaphragm forming one wall of said chamber, means connecting said latter diaphragm with the auxiliary valve, the chamber of the auxiliary motor communicating by means of a restricted passage with the transmission tube and having an orifice in its wall opening to the outer air, a lever movable by the stem of the main motor diaphragm when the latter opens the main valve, and means connecting the vent valve with said lever whereby movement of the lever opens the valve.

Signed by me at Syracuse, New York, this twenty-fifth day of March, 1925.

JAMES T. COWLEY.
